UNITED STATES PATENT OFFICE.

ADOLPH A. POEHNER, OF SAN FRANCISCO, CALIFORNIA, ASSIGNOR TO A. S. POEHNER,
OF SAN FRANCISCO, CALIFORNIA.

LEG-HOLDER.

1,230,512.

Specification of Letters Patent. Patented June 19, 1917.

Application filed July 22, 1914. Serial No. 852,391.

To all whom it may concern:

Be it known that I, ADOLPH A. POEHNER, a citizen of the United States, residing at San Francisco, in the county of San Francisco, State of California, have invented a new and useful Leg-Holder, of which the following is a specification in such full and clear terms as will enable those skilled in the art to construct and use the same.

10 This invention relates to a surgical appliance and its object is to hold the legs of persons being operated upon at a fixed distance apart.

An embodiment of the invention is shown 15 in the drawing in which the same reference numeral is applied to the same portion throughout, but I am aware that there are many modifications thereof.

Figure 1 is a side elevation of the complete device, and

Fig. 2 is a view at right angles to Fig. 1. The device has two curved stirrups 1 and 2, each of which is provided with hooks 3 and 4. The stirrup 1 is connected with a 25 tubular member 5, which member has an enlarged boss at 6, while the stirrup 2 is connected with a rod 7 which slides within the tubular member 5, a set screw 8 being used to secure the two members in a given position.

30 Copies of this patent may be obtained for five cents each, by addressing the "Commissioner of Patents, Washington, D. C."

When a person is to be operated upon the stirrups are placed against the legs and the device is adjusted to the desired distance, whereupon rubber bands 9 and 10 may be placed on the hooks 3 and 4 and around the 35 leg of the patient.

Having thus described my invention what I claim as new and desire to secure by Letters Patent of the United States, is as follows, modifications within the scope of the 40 claim being expressly reserved:

In a leg holder, a tubular member having a stirrup at one end thereof, a rod slidable within said tubular member and having a 45 stirrup at one end, a set screw to secure the rod and tubular member in a given position, a pair of hooks carried by each stirrup, and resilient means carried by the stirrups to secure a person's legs thereto.

In testimony whereof I have hereunto set 50 my hand this 14th day of July, A. D. 1914, in the presence of the two subscribing witnesses.

ADOLPH A. POEHNER.
